(57) **CLAIM**

The ornamental design for a wheel as shown and described.

DESCRIPTION

FIG. 1 is a front perspective view of a wheel;
FIG. 2 is a front view of the wheel of FIG. 1;
FIG. 3 is a rear view of the wheel of FIG. 1;
FIG. 4 is a rear perspective view of the wheel of FIG. 1;
FIG. 5 is a side view of the wheel of FIG. 1, wherein the opposite side view of the wheel of FIG. 1 is a mirror image thereof; and,
FIG. 6 is a top view of the wheel of FIG. 1, wherein the corresponding bottom view is identical thereto.
The evenly dashed broken lines in the drawings are for the purpose of illustrating portions of the wheel that form no part of the claimed design. The dot-dash broken lines define the bounds of the claimed design and form no part thereof.
